UNITED STATES PATENT OFFICE

WILLIAM E. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS

WIRE DRAWING CAPSTAN

Application filed July 13, 1929. Serial No. 377,958.

The present invention relates in general to the art of drawing wire. In particular, the invention deals with a process and apparatus by which the drawn wire, as it accumulates on the drawing block or drum, is caused to dissipate very rapidly the heat which has been generated therein by the drawing operation, whereby a marked improvement in the quality of the product is obtained.

10 It is well known that wire may suffer a serious impairment of its strength, particularly as regards its ability to stand up under twisting, if subjected in the drawing operation to excessive heat. I have discovered that 15 this impairment comes, not from the fact that the wire may have, for a relatively short time, an excessively high temperature, generated therein by its passage through a restricted die hole,—but rather from the fact 20 that in certain kinds of wire drawing operations, where the drawn wire accumulates on the block or drum in a considerable mass of overlying layers or convolutions, there is little or no chance for the heat to be radiated 25 from the wire; in consequence of this, the accumulated mass of wire is subjected on the block or drum to a detrimental "soaking" or prolonged retention of heat.

It has been proposed heretofore to cool the 30 capstan portion of a wire drawing block or drum by air or water introduced to its interior, but this expedient affords little, if any, relief for the conditions above set forth, because this cooling has no appreciable effect in 35 getting rid of the heat contained within the mass of convolutions that are pushed up progressively during the drawing operation onto the extension posts, or the like, above the drum. According to my invention, provision is made for air-cooling the interior of 40 the capstan portion of a wire drawing block or drum, and the discharge of cooling air from said capstan portion is so arranged that the ever-growing mass of wire accumulating above on the extension posts of the

block or drum is maintained at a sufficiently low temperature so that the wire suffers no detrimental effects, due to its prolonged retention in mass or bunched formation on said drum. Other and further objects and advantages of the invention will be made apparent in the following detailed description thereof, reference being had in this connection to the accompanying drawings, in which—

55 Fig. 1 is a top plan view illustrating the application of the invention to a plurality of wire drawing blocks or drums.

Fig. 2 is a view in end elevation of the apparatus shown in Fig. 1.

60 Fig. 3 is a larger scale side view, partly in section, showing one construction for a wire drawing block embodying the invention.

Fig. 4 is a view similar to Fig. 3, showing a modified construction.

65 Fig. 5 is a section on the line 5—5 of Fig. 4.

Like reference characters refer to like parts in the different figures.

70 Referring first to Figs. 1 and 2, I have shown, by way of example, a wire drawing bench 1 whereon are mounted, in the usual relation to the drawing dies 2, 2, a plurality of wire drawing blocks or drums 3, 3, the rotation of each of which, in the usual manner, procures the elongation of the wire by 75 pulling it through the associated die 2,—said wire being drawn progressively onto the capstan or base portion 5 of each drum 3, and the accumulating convolutions thereof moving upwardly in the usual way, to surround the annular series of posts 4, 4 which rise from said capstan. Each such capstan, designated at 5 in Fig. 3, and at 5' in Fig. 4, is so mounted as to be capable of partaking 80 in the usual manner, when desired, of the rotation of a vertical shaft or spindle 6, suitably journaled in the stationary bench 1. To this end, as shown in Figs. 3 and 4, the spindle 6 may have keyed thereto a plate 7, 85 providing a clutch surface in opposition, as 90

shown at 8, to a corresponding surface on the bottom of the block. The latter, through the medium of a vertically movable yoke, or the like, carrying a plurality of rollers 9, 9 (only 5 one being shown) can be raised, to disengage the clutch, for the termination of the drawing operation, or can be lowered, to engage the clutch, as desired, to start the drawing operation.

10 Referring now to Fig. 3, the rotary hollow capstan 5 therein shown comprises a bottom 10, a top 11, and a cylindrical side wall 12, the latter being connected to the bottom 10 by a plurality of suitable ribs 13, 13 which 15 bridge an annular space or opening 14 of said bottom, inwardly of the base flange 15 and depending skirt 16 of said side wall. In place of the usual stationary guard ring, surrounding the skirt 16 and preventing the 20 wire from getting beneath the block, I provide a hollow substantially annular member 17, stationarily mounted on the bench 1 concentrically with the capstan, and opening upwardly to the space 14, with its inner wall 25 making a running joint, as shown at 18, with a flange 19 of base 10. Its outer wall provides an annular recess 20, to receive the skirt 16, the latter making therewith a running joint, as shown at 21. Each stationary 30 hollow member 17, serving as a guard ring, with its interior thus connected to the substantially closed interior chamber of the rotary capstan 5, is in communication also, through a tubular extension 22, with a duct 35 or main 23, for a purpose to be hereinafter described.

In the wire drawing block of Fig. 4, of 40 slightly different construction, the top plate 11 is omitted, and the stationary hollow annular guard ring member 17, below the block, communicates in this case, not with the entire interior of the block, but with a substantially closed interior annular chamber 24 thereof, formed between the outer wall 12 and a concentric inner wall 25, providing connecting 45 ribs 26, 26 which bridge the open lower end 27 of said chamber. Otherwise the construction, and the mode of connection to the member 17, is substantially the same as shown in 50 Fig. 3.

According to the invention, the duct or main 23, common to the stationary hollow guard rings 17, 17 of all the drawing blocks on the bench 1, is connected, as shown in Fig. 55 2, to a source 28 of pressure or vacuum as embodied, for example, either in an air blower or in an air exhauster. As a result, assuming that a blower is used, a relatively large volume of cooling air is supplied to the interior of each drawing block, during the operation thereof, by its associated stationary hollow ring 17, and this air has a free escape from the block, according to my invention, 60 through numerous openings to the atmosphere, so that a constant circulation of the

cooling medium is maintained. As shown, the air thus blown in is free to escape, in a generally upward direction, through a multiplicity of openings 29 provided by the base flange 15 of each block, for direct impingement, exteriorly, on the convolutions of wire that are drawn onto the capstan portion 5 or 5', as the case may be. Furthermore, the outer wall 12 of each capstan provides a large number of relatively 75 narrow closely arranged and vertically elongated openings 30, 30, from which the air escapes radially to cool each convolution of wire while it is on the capstan, and before it is pushed up to join the mass of convolutions on the posts 4, 4 of the block. As each convolution, so partially cooled on the capstan, is forced up above said capstan to join the mass of convolutions accumulated on the posts 4, 4 of the block, it is further cooled by the air 80 discharging through a series of upwardly-directed openings 31, 31, so that by the time said convolution becomes merged in the bundle or mass, its temperature is very measurably lowered; the air from the openings 31, 31 impinges directly on the bundle or mass of wire, and thus keeps the temperature of said bundle or mass from rising.

The free circulation thus provided for the gaseous cooling medium, supplied in relatively large volume, is effective not only to cool the wire by direct contact, but also to cool the block by preventing any appreciable accumulation or storage of heat within the capstan portion 5 or 5', as the case may be. 95 Substantially the same cooling action, both as regards removal of heat from the capstan interior and direct impingement of the cooling medium on the individual convolutions of wire, is obtained when the source 28 is operated as an exhauster, rather than as a blower,—the cool air being drawn into the block through the openings 29, 29, 30, 30 and 31, 31, and removed therefrom by way of the stationary ring 17 and the pipe or main 23. 100 In either case, regardless of the direction of the circulation, the heat is rapidly and continuously removed and dissipated to the atmosphere; as a result, the interior space of the capstan is kept at a moderate temperature, and the consumption of lubricant therefore is much less than in the ordinary wire drawing block.

I have discovered furthermore that the continuous cooling action above described is 115 measurably promoted and improved by the circulation of air which is moisture-laden, instead of being in the normal relatively dry condition. To obtain this result, with the source of circulation 28 operating as a blower, I provide any suitable form of humidifier 32 in the inlet to the pipe or main 23, said humidifier being connected to any suitable water supply 33, whereby the air which is 120 supplied to the stationary hollow rings 17, 130

17 is humidified to the desired degree of saturation.

The gaseous cooling medium, such as air, which my invention employs, is permitted to circulate so freely and in such large volume that the heat, both of the block and of the wire, is very rapidly carried off; in consequence of this, the product, from the standpoint of its quality, strength, and twist capacity, is very greatly improved, notwithstanding the fact that its drawing may take place at a considerably higher speed than that which is the limit with drawing operations on the ordinary type of block. The gaseous cooling medium offers no problems whatsoever for its control or disposal, and it is not even necessary that the running joints 18 and 21 between each block interior and the stationary hollow ring 17 be tight, since the cooling medium, wherever it may escape, is capable of conducting away some of the heat from the interior of the capstan, and from the individual as well as from the massed convolutions of wire.

25 I claim:

1. In a wire drawing block, a hollow rotary capstan portion, a storage portion concentric with and overlying said capstan portion, to receive and accumulate in mass formation the convolutions of wire pushed up from the capstan portion by succeeding convolutions drawn thereon, and means for air cooling the interior of said capstan portion, the latter having a circular series of upwardly-opening apertures adjacent to and substantially surrounding the base of said storage portion, for the impingement of said cooling air against the individual convolutions of wire as they move off said capstan 40 portion onto said storage portion.

2. In a wire drawing block, a hollow rotary capstan portion, a storage portion concentric with and overlying said capstan portion, to receive and accumulate in mass formation the convolutions of wire pushed up from the capstan portion by succeeding convolutions drawn thereon, and means for air cooling the interior of said capstan portion, the latter having laterally-opening apertures 50 to direct said cooling air against the convolutions of wire thereon, and also having a circular series of upwardly-opening apertures adjacent to and substantially surrounding the base of said storage portion, for the impingement of said cooling air against the individual convolutions of wire as they move off said capstan portion onto said storage portion.

3. In a wire drawing block, a hollow rotary capstan portion, a storage portion concentric with and overlying said capstan portion, to receive and accumulate in mass formation the convolutions of drawn wire pushed up from said capstan portion, a base 65 flange on said capstan portion, an annular

stationary blast box below said flange, for supplying cooling air to the interior of said capstan portion, apertures in said flange to direct said air against the convolutions of wire on said capstan portion, and apertures in the upper part of said capstan portion, adjacent the base of said storage portion, to direct air from the interior of said capstan portion against said convolutions as they move from said capstan portion to join the mass 75 of convolutions on said storage portion.
